UNITED STATES PATENT OFFICE.

JESSE W. WOODWARD AND FRANK E. LEWIS, OF SHREVEPORT, LOUISIANA.

BOTTLE COOLER.

Application filed November 2, 1922. Serial No. 598,617.

To all whom it may concern:

Be it known that we, JESSE W. WOODWARD and FRANK E. LEWIS, citizens of the United States, residing at Shreveport, in the parish of Caddo and State of Louisiana, have invented certain new and useful Improvements in Bottle Coolers, of which the following is a specification.

This invention relates to means for maintaining bottled beverages in a sanitary condition and at a low temperature. The invention seeks to provide a bottle-cooling apparatus of such construction that bottled beverages may be had whenever desired and will be found in a palatable condition, the invention seeking to provide an apparatus which is simple in construction and easily operated to permit the withdrawal of a bottle from a cooling chamber. The invention is illustrated in the accompanying drawings and will be hereinafter fully set forth.

In the drawing:

Figure 1 is a perspective view of an apparatus embodying our invention showing the bottle container in position to permit the removal of a bottle;

Fig. 2 is a vertical section of the apparatus showing the bottle-containing compartment closed in full lines and showing the opened position in dotted lines.

In carrying out our invention, we construct the device in units each comprising a bottle container, a chamber for ice or other refrigerant, and a drip water chamber. These units are constructed of uniform size and design so that any number of units may be arranged side by side so as to provide a refrigerator of any desired capacity. Each unit comprises side walls 1, a back wall 2 and a front 3. A bottom 4 extends between the side walls, the front and the back, and the several walls may be connected by corner strips 5 so as to impart an ornamental appearance to the device and also reinforce the same, the corner strips being extended below the bottom so as to provide a support, as indicated at 6. Cross bars 7 may be secured upon the side walls, as shown in Fig. 1, with their outer surfaces flush with the surfaces of the corner strip so as to impart an ornamental appearance to the device and also reinforce the side walls. The intermediate cross pieces 7 furnish reinforcing supports for studs or pins 8 which project into the interior of the refrigerator for a purpose which will presently appear.

The front 3 has a lower panel immediately adjacent the lower end of the device, as indicated at 9, and also has an upper panel 10, which panels may be ornamented in any desired manner, as will be readily understood. The top of the device consists of a cover or lid 11 which is hinged at its rear end, as indicated at 12, whereby it may be readily raised and lowered, and the front 65 end of this lid or cover rests upon the upper edges of the side walls and the front so that it will make a close connection therewith and exclude air from the refrigerating chamber 13 which is arranged at the top of 70 the device. The said refrigerating chamber is defined by the side walls, the back and front and the lid or cover 11 and by a foraminous plate 14 which is removably supported by cleats 15 on the inner surfaces 75 of the several walls, as will be readily understood on reference to Fig. 2, it being noted that the said cleats are approximately in the horizontal plane of the lower edge of the top panel 10. Just above the lower panel 80 9 is a door 16 which swings in a horizontal plane and permits access to a drip pan 17 which is placed upon the bottom 4 of the refrigerator. Between the door 16 and the panel 10, an outwardly swinging door 18 is 85 provided, the said door 18 being hingedly mounted at its lower end so that it will swing downwardly as it swings outwardly. Within the casing and in rear of the said door 18, a bottle container 19 is pivotally 90 supported upon the studs or pins 8 previously mentioned. This container, it will be readily noted, is open at its top so that the cool air and the water formed by the melting ice may readily enter the container and 95 flow upon and around the bottles placed therein. A small quantity of ice may be placed in the bottom of the container before the bottles are placed therein if so desired, and openings or drains 20 are provided in 100 the bottom of the container so that the water formed by the melting ice may escape from the container into the drip pan 17 in an obvious manner. On the bottom of the container and near the front side of the 105 same, we secure depending notched brackets 21 which are adapted to engage over the pins or studs 8, as clearly shown in Fig. 2, so that the container may be rocked about the said studs. By having the pivotal 110 mounting of the container near the front side of the same, the filled container will be

overbalanced and will tend constantly to swing rearwardly so that it will be housed within the cabinet, the rearward movement being limited by the back of the container 5 bearing against the back wall 2 of the cabinet, as clearly shown in Fig. 2. Preferably, the container is constructed with an internal partition 22 so that two different kinds of beverages may be placed within one container and the upper front corner of the container is normally held to the door 18 by a latch 23 consisting of a finger or lug pivotally mounted at its upper end in the upper end of the door and adapted to engage over the upper edge of the front wall of the container, as shown in Fig. 2.

The container having been filled with bottles, as indicated at 24, is permitted to rock rearwardly so as to assume its normal position within the cabinet, and in this position it will hold the door 18 tightly closed by reason of its engagement with the locking finger 23 on said door. The warm air from the room is thus prevented from reaching the interior of the cabinet and a sufficient supply of ice or other cooling medium is placed in the cooling chamber through the top of the cabinet to completely fill said chamber so that it will last for a very considerable period. The cool air from the cooling chamber will, of course, descend and will play directly upon the bottles in the container 19 and will flow around the bottles so that they will be very thoroughly chilled with their contents and the said contents rendered palatable. When it is desired to withdraw a bottle, the door 18 is simply swung forwardly about its hinged connection and the container will be at once rocked upon the pins or studs 8 inasmuch as the finger 23 will, of course, move forwardly with the door 18. The finger 23 should be long enough to accommodate the relative angular movements of the container and the door, and remain in engagement with the container even after the parts reach the position shown by the dotted lines in Fig. 2. One or more bottles may be then easily lifted from the container, as is obvious. If it should be desired to remove the container in order to clean the same or for any other purpose, the finger 23 is swung about its pivotal mounting in the door 18 so as to clear the edge of the container, 55 after which the container may be lifted slightly to enable the brackets 21 to clear the studs 8, whereupon the container may be readily withdrawn through the door opening in the front of the cabinet.

60 Our improved refrigerating apparatus is very simple in construction and is not apt to get out of order. It readily lends itself

to ornamentation and by being constructed in units of uniform style and size may be doubled or extended, as circumstances may demand. It is possible also to arrange units at different places within a store room so that the space may be most advantageously utilized. The bottled beverages will be maintained in a sanitary condition and may be easily withdrawn when desired without subjecting the user to the annoyance caused by merely submerging bottles promiscuously within a vessel containing ice water.

Having thus described the invention, 75 what is claimed as new is:

1. An apparatus for the purpose set forth comprising a casing, a downwardly and outwardly swinging door in the front side of the casing, a container mounted adjacent the door within the casing independent of the door for rocking movement, and means for connecting the container with the door whereby the opening of the door will rock the container through the front of the casing.

2. An apparatus for the purpose set forth comprising a casing, a downwardly and outwardly swinging door in the front side of the casing, a container independently and removably mounted within the casing immediately in rear of said door for rocking movement, and a latching finger pivotally mounted in the upper end of the said door and adapted to engage over the front wall of the container.

3. An apparatus for the purpose set forth comprising a casing, a downwardly and outwardly swinging door in the front side of the casing, a container arranged within the casing immediately in rear of said door, means for detachably connecting the container with the door, studs on the side walls of the casing adjacent the said door, and notched lugs secured to the bottom of the container near the front wall thereof and adapted to engage the said studs whereby the container will be removably and pivotally supported within the casing independently of the door.

4. An apparatus for the purpose set forth including a top ice chamber having holes in the bottom thereof to provide for dripping of the water, a swinging door, and a container for bottles to be cooled disposed below the ice chamber and attached to the door, said container having holes in the bottom thereof to provide for removal of the drip water.

In testimony whereof we affix our signatures.

JESSE W. WOODWARD. [L.S.]
FRANK E. LEWIS. [L.S.]
